UNITED STATES PATENT OFFICE.

BEATRICE IRWIN, OF NEW YORK, N. Y.

LIGHT-FILTER.

1,351,756.

Specification of Letters Patent. Patented Sept. 7, 1920.

Application filed August 22, 1918. Serial No. 250,920.

To all whom it may concern:

Be it known that I, BEATRICE IRWIN, a subject of the King of England, and a resident of New York city, in the county of New York and State of New York, have invented certain new and useful Improvements in Light-Filters, of which the following is a specification.

My invention relates to improvements in light filters or screens or shades. The main object of the invention is to provide an arrangement of this class which is not only easily and cheaply manufactured and which has artistic and healthful merit but also one which will give substantial and long service in spite of its cheapness. Furthermore filters or shades made in accordance with my invention lend themselves admirably to various color schemes and especially for hand coloring in accordance with individual requirements and tastes.

In carrying out my invention, I construct the body portion of the filter or shade of paper, and while the paper should be relatively stiff it should also have sufficient translucency to permit light to pass therethrough for lighting purposes.

I am aware that many forms of socalled Chinese and Japanese lanterns made of paper and also crape paper shades have long been in use, but so far as I am aware none of these have been constructed of such stiff and strong paper as I employ, but are made of relatively thin and weak paper so that they are easily gotten out of shape and soon become dilapidated under severe service conditions. Such devices also do not have various other features and advantages of my improvements which will more clearly appear from the detailed description given below taken in connection with the accompanying sheet of drawings which forms a part of this specification.

In the drawings Figure 1 is an elevation of a light filter embodying my improvements in one form, and Fig. 2 is a plan view thereof.

Referring to the drawings, 1 represents the base of the filter support and 2, 2 uprights carrying a cross piece 3 from which the filter proper 4 is supported by a cord 5 hung over a pin 6 in the top of the cross piece 3. In the form shown the filter portion 4 is composed of a sheet of paper formed into cylindrical shape, the two meeting edges being secured together in any suit-

able manner as by small bolts 7. A source of light comprising an incandescent electric light bulb is shown at 8 within the cylindrical filter 4, the same being supported by the usual cord 9 which passes through a hole in the cross piece 3, down through a hole in one of the uprights 2 and through a hole in the base portion 1 to the screw plug 10 of any suitable variety. However, any other suitable source of light may be employed. It will be noted, however, that the filter 4 is shaped to screen the most of the light rays from the source of light within it, that is, the most of the light rays which are useful for lighting purposes. The apparatus may be placed on a table, bracket, stand or in any suitable place.

The paper from which the filter 4 is made must be carefully chosen and I preferably use a paper having a stiffness like that of Whatman's Royal having a weight of approximately 44 pounds per ream of sheets size 19 inches by 24 inches. However, under some circumstances, and especially in very small filters a thinner paper may be used such as that having a stiffness like that of Whatman's Demy having a weight of approximately 25 pounds per ream of size 15 inches by 20 inches. Also in cases where more rigidity is desired and it is not important that a large percentage of the light be transmitted, a heavier and stiffer paper may be used, such as that having a stiffness and translucency of Whatman's Imperial having a weight of approximately 72 pounds per ream of size 22 inches by 30 inches. However, I preferably select a paper which has a sufficient thickness and stiffness to retain the shape and form of the filter unaided, that is, when supported in place it requires substantially no reinforcing ribs or other means to maintain its shape such as has been customarily used in the so-called Chinese and Japanese lanterns and crape paper shades above mentioned. Also, I preferably select a paper having a translucency of about 25% or more, that is to say one which does not reduce the lighting power of the source of light by more than about three quarters, or which does not prevent the passage therethrough of more than about three quarters of the light rays from the source. Generally, however, I use a paper which permits the passage of a much larger percentage of the light rays as for example a paper having 50% translucency.

By using paper of the kind described I find that while it is sufficiently translucent to permit enough light to pass therethrough for lighting purposes, nevertheless it substantially completely screens the source of light within it, that is, the actual source of light and its outline is not visible through the filter but the filter itself by reason of the rays coming therethrough is made to appear as the source of light, whereby the light does not appear to come from a highly luminous spot but from all over a broad surface radiating light rays relatively soft in character.

15 In order to prevent inflammation or charing of the filter from the heat from the source of light, I treat the paper to render it fire-resistant. This I do by applying thereto with a brush a 10% solution of ammonium phosphate. However, the paper may be treated in any other suitable manner to render it fire-resistant. I find it most effective to treat the paper with the solution on the side thereof nearest the source of 25 light.

The paper from which the filter is made is preferably white and of a texture to take coloring matter such as water colors, aniline dyes and the like. Filters so constructed I 30 find are admirable for carrying out various color schemes by having such coloring matter of various colors or shades applied thereto as illustrated in Fig. 1. The coloring may be done by hand to suit particular requirements and tastes and in accordance 35 with color science to produce curative or other desirable effects on the human system. The coloring matter, I preferably apply with a brush and on the outside of the filter 40 *i. e.* on the opposite side thereof from the source of light. After the coloring matter has been applied I preferably harden it or fix or set the color in the paper by applying thereto a 10% solution of tannic acid as 45 with a brush. Any other suitable fixing treatment may be employed however, I preferably color the filters without definite configuration, *i. e.* without picturing or definite forms, but rather with more or less cloud 50 effect with the different colors or shades running into one another or gradually merging into one another, and combining stimulant, sedative and recuperative color values or any two of them, as illustrated in Fig. 1, as 55 I find that such arrangement is generally more advantageous and desirable.

If the filters are to be used under conditions where they are likely to become wet, I 60 preferably apply a waterproofing treatment thereto to make them more water-resistant. For this purpose I prepare a solution of 5 ounces of bleached shellac and 1 ounce of borax, dissolved in one pint of water, and brush a layer of this solution onto the 65 faces of the filter to be protected.

It has heretofore been suggested that a corrugated paper be used for a light filter or shade in order to give it sufficient stiffness and for other purposes. But corrugated paper largely destroys the desired effect so I 70 use a non-corrugated paper and use a paper of definite stiffness to avoid the necessity of corrugations for the purpose of stiffening it and with the coloring matter on it the non-corrugated filter produces an entirely different effect from that produced by a corrugated paper filter with the similar coloring matter on it. The coloring matter of various shades or colors preferably run harmoniously into one another as illustrated 80 in Fig. 1 of the drawing, the light filtering through the variously colored portions, the colored portions being translucent and the coloring matter being insufficient to decrease the light coming through the filter to render 85 it ineffective for lighting purposes.

• It will be understood, of course, that the invention is not limited to any particular shape or size of filter, since they may be made in a great variety of shapes and sizes, 90 to suit various situations and conditions. Also any means for securing them in place, and any suitable source of light may be used. Many other changes and modifications may be made and the invention embodied in 95 widely differing forms, and consequently, while I have described one embodiment of my invention and in great detail, I do not desire to be limited to such details but desire to cover all forms having the combination of 100 features set forth in any one or more of the appended claims or their equivalents.

What I claim is:

1. A light filter composed of paper, and adapted to screen the light rays from a 105 source of light, the paper having such a thickness and translucency that it renders the source of light substantially invisible therethrough, while permitting sufficient light rays to pass therethrough for lighting 110 purposes and make the broad surface of the paper filter appear as the source of light, the paper having coloring matter of various shades or colors thereon with the colors or shades gradually merging or running into 115 one another to cause the light coming from the filter to be variously colored, the coloring matter being insufficient to decrease the light coming through the filter to render it ineffect 120 for lighting purposes.

2. A light filter composed of paper and shaped to screen the light rays from a source of light, the paper having such a thickness and translucency that it renders the source of light substantially invisible therethrough, 125 while permitting sufficient light rays to pass therethrough for lighting purposes and make the broad surface of the paper filter appear as the source of light, the paper having coloring matter of various shades or col 130

ors thereon forming a combination of stimulant, sedative and recuperative color values or any two of them, with the colors or shades gradually merging or running into one another to cause the light coming from the filter to be variously colored, the coloring matter being insufficient to decrease the light coming through the filter to render it ineffective for lighting purposes.

10 3. A light filter composed of paper and shaped to screen the light rays from a source of light within it, the paper being substantially plane as distinguished from corrugated and having such a thickness and translucency that it renders the source of light within substantially invisible therethrough, while permitting sufficient light rays to pass therethrough for lighting purposes and make the broad surface of the paper filter appear as the source of light, the paper having coloring matter of various shades or colors thereon on the opposite side thereof from the source of light, whereby the light appears to radiate from the coloring matter with the colors or shades gradually merging or running into one another to cause the light 45 coming from the filter to be variously colored, the coloring matter being insufficient to decrease the light coming through the filter to render it ineffective for lighting purposes.

20 4. A light filter composed of paper and having coloring matter of various shades or colors thereon with the colors or shades gradually merging or running into one another to cause the light coming from the filter to be variously colored, the coloring matter being insufficient to decrease the light coming through the filter to render it ineffective for lighting purposes.

4. A light filter composed of paper and

shaped to screen the light rays from a source of light within it, the paper being substantially plane as distinguished from corrugated and having such a thickness and translucency that it renders the source of light within substantially invisible therethrough, 35 while permitting sufficient light rays to pass therethrough for lighting purposes and make the broad surface of the paper filter appear as the source of light, the paper having coloring matter of various shades or colors 40 thereon on the opposite side thereof from the source of light, whereby the light appears to radiate from the coloring matter with the colors or shades gradually merging or running into one another to cause the light 45 coming from the filter to be variously colored, the coloring matter being insufficient to decrease the light coming through the filter to render it ineffective for lighting purposes.

Signed at Watkins, in the county of Schuyler and State of New York, this 20th day of August, A. D. 1918.
